UNITED STATES PATENT OFFICE.

JOHN F. JONES AND WILLIAM T. STUCKEY, OF MONTGOMERY, ALABAMA.

DESIGN FOR A SHADE-BRACKET.

SPECIFICATION forming part of Design No. 34,862, dated July 30, 1901.

Application filed February 14, 1901. Serial No. 47,386. Term of patent 14 years.

To all whom it may concern:

Be it known that we, JOHN F. JONES and WILLIAM T. STUCKEY, residents of Montgomery, in the county of Montgomery and State 5 of Alabama, have invented and produced a new and original Design for a Shade-Bracket, of which the following is a specification, reference being had to the accompanying drawings, forming a part thereof.

10 Figure 1 is a side elevation of the shade-bracket made in accordance with our new design. Fig. 2 is a section on line 2 2 of Fig. 1. Fig. 3 is a perspective view of the shade-bracket embodying the present design.

15 As shown in the drawings, the leading or material feature of our design consists of a cylindrical shank 3, at one end of which the material thereof extends laterally at an angle of one hundred and thirty-five degrees and 20 is straight and is round in cross-section, as shown at 5. From this latter portion, which forms the stem of the hook, extends an arcuate web portion 4, which is somewhat greater

than one-half of a circle. The outer end of this arcuate portion is bent up to form the 25 bill of the hook 6, which is straight and lies parallel with the portion 5. The portion 6 is cylindrical, while the portion 4 of the hook is flattened on its inner face. The distance between these two sides is less than the diameter of the circular portion of the opening, 30 as shown in Fig. 1.

Having thus described our invention, what we claim as new, and desire to secure by Letters Patent, is—

35 The design for a shade-bracket as herein shown and described.

In testimony whereof we have signed our names to this specification, in the presence of two subscribing witnesses, on this 8th day of 40 January, 1901.

JOHN F. JONES.

WILLIAM T. STUCKEY.
